UNITED STATES PATENT OFFICE.

GEORGE E. WILLERS, OF LAWRENCEBURG, INDIANA, ASSIGNOR TO A. D. COOK, INC., OF
LAWRENCEBURG, INDIANA, A CORPORATION OF INDIANA.

LUBRICATING DEVICE FOR PUMPS.

Application filed January 15, 1925. Serial No. 2,698.

My invention relates to lubrication of the moving parts serving to operate pumps, and particularly double plunger pumps.

It has as its object the provision of a simple structure, automatically operative to maintain the various rocker arms, gears, shafts and the like in a shower of oil at all times.

In pumps of the type noted, which have heavy work to perform, and are called upon for silent operation, which means accurate relation to stroke of the rods, and smooth running of the slides, cams, gears and the like, the lubrication is a serious problem. Taking advantage of the rocking of the pump rod operating members, I am enabled to pump oil into a pan at the top of a pump operating device and spill it through slots into the interior of the pump, in such a way as to lubricate the entire device by a fountain of oil, at all times of its operation, returning the oil to the pan by means of any suitable pump. Also I encase the working parts except the rod connections, and in order to prevent water from getting into the casing, I provide a baffle of special design.

I accomplish my objects by that certain construction and arrangement of parts to be hereinafter more specifically pointed out and claimed.

In the drawings:

Figure 1 is a side elevation of a pump of one particular type to which my invention is well applicable.

Figure 2 is a detail elevation of the two rocker levers of the pump with the oil device at the journal of the upper one.

Figure 3 is an end elevation of the parts shown in Figure 2.

Figure 4 is a vertical cross section of the spill pan.

Figure 5 is an elevation, half in section of the baffle device and connections, and

Figure 6 is a detail elevation of the connection of baffle for the upper sliding bearing thereof.

The pump selected for illustration has a base 1 and standards 2 in which are journals for the several shafts. Around the standards, and covering them at the top, sides and back, is a hood or cover 3, which rests on the base. The base will have any suitable trap or basin for oil from which it is to be pumped to the top of the frame.

This structure being of common type and structurally unnecessary to illustrate the invention, has not been shown in the drawings, since it is the oil distribution and frame protection that is the essential. 60

The guide rods for the pump rod cross heads are located at 4, and the cross heads are shown at 5 and 6.

On the shaft 7, which may be a rigid shaft, is the top rocker having a long journal 8 on the shaft, and has arms 9 and 10. The arm 10 is connected as desired to one of the cross heads, and the arm 9 has a slide-way 11 therein. On the shaft 12 is a like rocker having arm 13 connected to the other cross head, and the arm 14, having a slide-way 15 therein. A pair of large gears 16, 16, are supported rotatably in the two side frames, and are connected by an eccentric rod 17, which carries a journaled slider 18, 75 that engages in the slideways 11 and 15, thereby rocking the two arms.

The gears 16 are driven by pinions 18^a on a shaft 19 also journaled in the frame, and driven by means of a gear 20, or a pulley 80 and belt, as the case may be.

This particular structure of pump narrows down the parts to a compact relation as is well shown in Figure 3.

On the sleeve portion or journal 8 of the top rocker is secured in any suitable way, an oil pan 21.

This pan has notches 22 distributed about its sides and ends, and is kept filled with oil from the delivery pipe 23, located above 90 the pan. Holes are also provided in the corners of the pan for the same purpose.

The movement of the pan is never such as to bring it out of position to receive and retain for distribution the oil pumped from 95 the pipe. That is to say the pan is mounted and made large enough so that it will never rock out of range.

The oil is spilled out through the notches in the sides and ends of the pan, in such a 100 way as to fall in a shower, bathing the various parts of the pump which have been described. The pan is as wide as the parts necessary to be showered, are wide as assembled.

The protective casing keeps out dust and dirt, and prevents the oil from splashing. Since, however, the casing or shell must be left open at the front for the passage of 110 the rocker arms, and since the leakage likely

to occur through faulty packing could find an entrance into the shell at this point, I provide a special device for preventing such influx of water.

5 Instead of providing special leak preventing packing boxes, I provide a baffle device which is so mounted as to protect both glands, i. e., where the outer rod passes into the well casing and where the inner rod 10 passes into the outer rod.

The connections of the two rocker arms with the cross heads 5 and 6, have not been shown in detail, and any form of connection will do, which is forward of the axis 15 of the two rods, and far enough from the rods themselves as to leave room for a baffle. Mounted fast on the lower gland 30 for the outer pump rod is a collar 31, to which is screwed the lower end of a cylindrical baffle plate 32, said baffle plate being 20 left open at the front for the passage of the cross head of the outer pump rod.

A sleeve 33 is arranged over the inner pump rod which sleeve has a cross piece 34 25 thereon, to which the sides of the baffle are secured as by screws.

The result of this structure is that the baffle does not interfere with the movement 30 of the lower cross head, and does not interfere with the upper cross head, as it is not long enough to reach this cross head in its lowest position. However, the glands for both rods are protected on the side toward the mechanism casing, so that leaky 35 glands will not result in oil getting into the said casing through the openings necessary for the movement of the rocker arms and connecting rods.

Thus I provide for a lubrication of double plunger pumps of the rocker arm type, 40 in such a way that attention by an engineer is not necessary. These pumps are often operated continuously, for long periods of time, and cannot be constantly watched, and 45 by my invention I have provided for a lubrication feature that is fool-proof to a high degree.

Having thus described my invention, 50 what I claim as new and desire to secure by Letters Patent, is:—

1. In a pump device, a base, a pump rod,

mechanism on said base for operating the rod comprising a rocking lever, an oil pan mounted on said lever and adapted to be rocked thereby and holes in the sides of the 55 pan to permit leakage of oil from the pan to drop it upon the said mechanism, an oil supply pipe, said pan being so positioned as to receive oil from said pipe.

2. In a pump device, a base, a pump rod, 60 mechanism on said base for operating the rod comprising a rocking lever, an oil pan mounted on said lever and adapted to be rocked thereby and holes in the sides of the 65 pan to permit leakage of oil from the pan to drop it upon the said mechanism, an oil supply pipe, said pan being so positioned as to receive oil from said pipe, a housing about said mechanism adapted to enclose it except for connections to said rod, and 70 a baffle for preventing water from entering the housing when leaking about said pump rod.

3. In a pump device, the combination of 75 double plunger rods, an operating mechanism, comprising two rocker arms for operating the rods, and driving means for the rocker arms, one of said rocker arms being mounted above the remainder of the operating mechanism, an oil pan mounted on the 80 upper rocker arm so as to rock on the same axis therewith, and an oil supply for providing oil to said pan, said pan having openings in its walls, to permit oil to run out as the pan rocks from side to side with 85 said upper rocker arm.

4. In a pump device, the combination of 90 double plunger rods, an operating mechanism, comprising two rocker arms for operating the rods, and driving means for the rocker arms, one of said rocker arms being mounted above the remainder of the operating mechanism, an oil pan mounted on the 95 upper rocker arm so as to rock on the same axis therewith, and an oil supply for providing oil to said pan, said pan having slots in its walls, to permit oil to run out as the pan rocks from side to side with said upper rocker arm, said oil pan being secured to said rocker arm at its line of support.

GEORGE E. WILLERS.
